Primary Examiner — Bao-Yen T Nguyen*Assistant Examiner* — Amanda J Berlinski(74) *Attorney, Agent, or Firm* — Capitol City TechLaw(57) **CLAIM**

The ornamental design for a nebulizer compressor, as shown and described.

DESCRIPTION

FIG. 1 is a front, top, and right side perspective view of a nebulizer compressor showing our new design;

FIG. 2 is a front, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The dash-dash broken lines seen in the drawings depict portions of the nebulizer compressor that form no part of the claimed design. The dot-dash broken lines seen in the drawings represent a boundary and form no part of the claimed design. Features depicted within the boundary lines form no part of the claimed design.
